UNITED STATES PATENT OFFICE.

WALKER J. BOUDWIN, OF SALT LAKE CITY, UTAH.

CLASSIFIER AND DEWATERER.

1,140,793.

Specification of Letters Patent.

Patented May 25, 1915.

Application filed November 23, 1914. Serial No. 873,615.

To all whom it may concern:

Be it known that I, WALKER J. BOUDWIN, a citizen of the United States, residing at Salt Lake City, in the county of Salt Lake and State of Utah, have invented certain new and useful Improvements in Classifiers and Dewaterers, of which the following is a specification.

My invention relates to an apparatus for classifying, washing, mixing, and dewatering sands and slimes of ore wherein the ore is fed up an inclined surface and out of water onto an appropriate draining surface; and my invention consists of the parts 10 and the constructions, arrangements and combinations of parts which I will herein-after describe and claim.

In the accompanying drawings forming part of this specification and in which similar reference characters indicate like parts in the several views, Figure 1 is a top plan view of an apparatus constructed according to my invention. Fig. 2 is a vertical cross sectional view of the same. Fig. 3 is a cross sectional view of an apparatus of modified form. Fig. 4 is a side elevation of another modified form of apparatus. Figs. 5, 5^a, 6, and 7 illustrate modified forms of conveying devices. Fig. 8 is a cross sectional view 20 of another modification showing the use of my invention, as a drier and defrother on flotation concentrates, and the like. Fig. 9 is an enlarged sectional detail of a fragment of the cone and its attached overflow or weir of Fig. 8.

A leading object of my invention is to provide a simple and effective apparatus for classifying, washing, mixing and dewatering sands and slimes of ore, and to this end 30 I mount upon a suitable foundation or framework, a pan-like structure of suitable diameter and which comprises a cone, A, the periphery of which is turned at a suitable angle to form a rim and an annular trough, 40 or gutter, B, which latter is of substantially conical form in cross section, said up-turned portion or rim being provided with suitable outlets, E, for the overflow and said rim or up-turned portion of the cone being supplied 50 with a vertical wall or rim, C, in an intermediate part, said wall or rim being in a plane below the plane of the apical portion of the cone and acting as an overflow or weir, behind which is formed the overflow 55 trough or gutter, G, which communicates with the aforesaid outlets, E.

At the apex or central portion of the cone, A, there is provided an opening through which the ore particles, advanced up the inclined sides of the cone, as hereinafter described, may be discharged, said opening communicating with a vertical pipe, D, below the lower or discharge end of which is suitably mounted a belt or other conveyer, I. In the present case this belt or conveyer is 60 shown as having its upper run mounted upon troughing rollers, a, which give said run of the belt a trough-shape in cross section for better holding the concentrates which are delivered to the belt through the 65 aforesaid pipe.

Appropriately mounted vertically in line with the apex of the cone, A, is a shaft, F, which is designed to be driven by any suitable mechanism, as the worm and worm-wheel, K, K', shown, the lower end of the shaft being appropriately connected to suitable downwardly inclined arms, G', of which there may be any desired number. These arms are inclined so that they are disposed 75 substantially parallel with the upper inclined surface of the cone, A; suitable braces, b, or the like may be employed to support the outer portions of the arms.

The arms, G', which, as before stated, are 80 connected to and carried by the vertical revoluble shaft, F, have their under surfaces provided with some suitable form of rabbles, blades, or flights, or equivalent means which are designed to engage and 85 progressively advance the sands and slimes up the inclined surface of the cone to the central discharge thereof. Various means may be employed for effecting this result and, therefore, I show the rabbles, or flights 90 as in the form of hoes, H, in Fig. 2, which hoes will be set at such an angle to the arms as is best suited for the purpose. If preferred, the flights may be in the form of disks, H², as shown in Figs. 5, 5^a which are 95 rotatably mounted in brackets, or hangers, H³, secured to the inclined arms, said disks being angularly arranged with respect to the arm so that during the sweep of the latter over the surface of the cone, A, the 100 disks will push aside and progressively 105 crowd the sands and slimes upwardly over the surface of the cone, to the central discharge thereof.

In Figs. 6 and 7, I have shown the arms 110 in the form of revoluble shafts, G'', provided with a spiral conveyer, H', and to

which rotation may be imparted through the medium of pinions, S, on the upper ends of the shafts and engaging gear wheel, M, on the lower end of the vertical shaft, said gear being shown in the form of a circular rack which is supported and held against rotation by hangers, M', or other well known means, which specific arrangement forms no essential part of my present invention. With this construction it will be understood that as the arms are carried around to sweep over the inclined surface of the cone, A, they are at the same time rotated so that the spiral conveyers will engage and progressively advance the sands and slimes out of the water and along and over an unsubmerged portion of the inclined surface to the aforesaid central discharge.

Suitably mounted above the cone, A, is an annular feed trough, J, into which the sands and slimes are fed, from any suitable source of supply, said annular feed trough having a series of short pipes, K'', on its bottom, and which are designed to act as a feed-distributer and which deliver the sands and slimes to the surface of the cone in advance of the rabbles, flights or means conveying the said sands and slimes up the inclined surface of the cone, it being understood that the annular feed trough is suitably connected to the arms or otherwise arranged so that it may be rotated in unison with the vertical shaft, which carries the aforesaid arms.

In operation, the feed of pulp is delivered to the annular trough, J, and it is distributed by the latter in the path of the revolving arms. The solids or heavy material settle on the inclined surface of the cone and are thence conveyed or rabbled up the said surface of said cone and onto an unsubmerged part thereof and are discharged through the opening at the apex thereof and into the pipe or passage, D, and finally onto the conveyer, if the same is employed. During this operation the water and some solids overflow around the gutter or weir, C, which is disposed below the plane of the apical portion of the cone, and thus complete the function of my machine.

Owing to the circular form of the cone, I am enabled to obtain a maximum settling area as well as a longer particle travel of the sands and slimes both in and out of the water, which is contained in the gutter formed around the peripheral edge, as shown, and in which gutter the lower of the rabbles or flights operate.

The circular overflow due to the presence of the slimes and letting them go with the long particle travel and the greater draining area gained by a machine of the type shown, is important in the art of dewatering, giving the pulps an acid bath or classifying, by which latter, I mean the washing

of the slimes and letting them go with the overflow, if so desired. This would be obtained by speeding up the machine so as to cause the fines to be carried, if in suspension, by the agitation of the arms and rabbles. 70

The main object of my invention is to employ the aforesaid mechanism as a dewaterer of pulp concentrates and to give the pulp an acid bath.

In Fig. 3, I show a modification of the before described apparatus, wherein the ore may be subjected to an acid bath, and to this end, the cone, A', is stepped between its center and circumference to form a second gutter-like portion, B', in which a second series of arms, G'', with complementary rabbles or flights operate, these arms being inclined substantially parallel with the inclined surface of the conical portion, A'', and which portion has at its center, the opening and discharge tube, D', for the concentrates which are dragged over the surface of the cone to the apex thereof. A suitable annular trough, J', revolvable with the arms and vertical shaft, as well as the arms, G, and ore-pulp trough, J, is designed to receive a suitable acid, when the pulp is to be subjected to acid treatment. In this case, the sands and slimes are rabbed or conveyed out of the water and upwardly over the inclined surface of the cone, A', and they are discharged into the acid bath in the gutter, B', formed between the uppermost surface of the cone portion, A', and the lowermost surface of the cone 100 portion A'', and are finally rabbed or directed out of the acid bath and up the surface of the cone, A'', and delivered at the center thereof, as before described.

In Fig. 4, an apparatus is shown wherein a series of the aforesaid conical pans or trays are nested or mounted one above the other, each of the pans having its central discharge opening communicating with the other and the several pans or trays delivering to a conveyer, and each pan having its own overflow, and which arrangement may be used, if desired, and particularly where space is an important consideration.

The apparatus disclosed in Fig. 8 possesses the leading characteristics of those before mentioned, and shows but another application of my invention. In this instance, the apparatus may be used, as a drier and defrother on flotation concentrates or any other concentrates. The apparatus of Fig. 8 includes the cone-shaped pan, A'', the up-turned rim of which is provided with an overflow or weir, C'', which has its upper end flared or turned inward to confine the froth which may accumulate on the surface of the pulp, said overflow or weir being provided with openings, c, which are in a plane below the plane of the apical portion of the cone and which permit the liquid to flow into 130

the annular gutter, B³, surrounding the weir and to be finally discharged at the points of overflow. The apparatus of Fig. 8 is provided with an annular spray pipe, L, which 5 is designed to act as a defrother; to this end it is positioned adjacent the upper surface of the pulp and in such relation thereto that its spray may act directly upon the froth accumulating under the inturned up- 10 per edge of the overflow weir, C³, said spray pipe being supplied with air, steam or water, admitted thereto through an appropriate pipe, d, which may pass through the central discharge tube of the apparatus, as 15 shown. The upper portion of the cone, A³, of Fig. 8, is also provided with a steam jacket, U, through which steam may be admitted by a pipe, e, and from which steam jacket a suitable return pipe, f, may lead. 20 In this case the rotary arms, G⁴, with their rabbles or flights h advance the sands or slimes out of the water and onto and over the part of the inclined surface which is not submerged and finally onto and over the 25 upper inclined surface of the steam jacket, and which latter surface acts as a hot plate or drier for the particles which pass thereover.

As before described, the apparatus shown 30 in Fig. 2 will be found useful as a drier and defrother on flotation concentrates and is equally useful for drying in other concentrates.

Having thus described, my invention 35 what I claim as new and desire to secure by Letters Patent is:

1. In apparatus of the character described, a circular pan having a conical portion and an upturned rim forming a gutter at the base of the cone, and members operable over the conical surface of the pan having means for progressively moving sands and slimes upwardly over the inclined surface of the pan and over an un- 40 submerged portion thereof, said pan having means for discharging solids at its apex and having an overflow lying in a plane below the plane of the apical portion of the cone.
2. In apparatus of the character described, a circular pan having a conical portion and an upturned rim forming a gutter at the base of the cone, said up-turned portion having a vertical flange extending 45 from an intermediate part over the edge of which water and slimes overflow, and members operable over the conical surface of the pan having means for progressively moving sands and slimes upwardly over the inclined surface and over an unsubmerged portion thereof, the overflow of the pan being in a plane below the plane of the apical portion of the pan and said apical portion of the pan having means for discharging 55 solids.

3. In apparatus of the character described, a circular pan having a conical portion and an upturned rim forming a gutter at the base of the cone, said up-turned portion having a vertical flange extending from 70 an intermediate part over which water and slimes overflow, and arms operable over the conical surface of the pan having means for progressively moving sands and slimes upwardly over the inclined surface and over 75 an unsubmerged portion thereof, said overflow being in a plane below the plane of the apical portion of the cone and said pan having a discharge opening for solids in its apex.

4. In apparatus of the character described, a circular pan having a conical portion, an up-turned rim forming a gutter at the base of the cone, inclined arms arranged substantially parallel with the inclined surface of the pan having means for progressively moving sands and slimes upwardly over said surface and over an unsubmerged portion thereof, said pan having an overflow in a plane below the plane of 90 the apical portion of the cone and having means for discharging solids at the apex, a vertical shaft to which the inner ends of the arms are connected, and means for rotating said shaft to cause the arms to sweep over 95 the conical portion of the pan.

5. In apparatus of the character described, a circular pan having a conical portion and an upturned rim forming a gutter at the base of the cone, arms operable over 100 the conical surface of the pan having means for progressively moving sands and slimes upwardly over the inclined surface of the pan and over an unsubmerged portion thereof, said pan having a discharge opening for solids at its apex and having an overflow in a plane below the plane of the apical portion, and an annular feed trough movable with the arms having outlets adapted to deliver pulp upon the inclined surface 110 of said pan.

6. In apparatus of the character described, a circular pan having a conical portion and means forming at the base thereof an annular gutter, arms operable over the 115 inclined surface of the pan having means for progressively moving sands and slimes upwardly thereover and over an unsubmerged portion thereof, said pan having a central discharge for the sands and slimes, 120 and having an overflow in a plane below the plane of the apical portion, and an annular feed trough movable with the arms having means for supplying its contents to the inclined surface of the pan.

7. In apparatus of the character described, a circular pan having a conical portion, and an up-turned rim forming a gutter at the base of the cone and devices operable in a circular path over the conical sur- 130

face of the pan, said devices having means for progressively moving the sands and slimes upwardly over the inclined surface of the pan and over an unsubmerged portion thereof, said pan having means for discharging solids at its apex and having an overflow lying in a plane below the plane of the apical portion of the cone, and means for heating the unsubmerged por-

tion of the pan whereby said portion acts 10 as a drier for the sands and slimes passing thereover.

In testimony whereof I affix my signature in presence of two witnesses.

WALKER J. BOUDWIN.
